I claim the ornamental design for a “trigger lock for air rifles and air hand guns”, as shown and described herein.

DESCRIPTION

FIG. 1 is a front elevational view of the trigger lock for air rifles and air hand guns showing my new design.

FIG. 2 is a rear elevational view of the design of this invention.

FIG. 3 is a right side elevational view of the design of this invention.

FIG. 4 is a left side elevational view of the design of this invention.

FIG. 5 is a top plan view of the design of this invention, and, FIG. 6 is a bottom plan view of the design of this invention.
